LESTER RAY THORPE, OF EAST BAKERSFIELD, CALIFORNIA

FINGER BOARD

Application filed July 22, 1929. Serial No. 380,044.

My invention relates to what is known in the art of well drilling and pumping as finger boards, or devices for supporting within a derrick pipe or tubing as it is broken up and its sections stacked in vertical position in the derrick so as to be in convenient position for use in reconnecting them into a string to be let down into the hole.

It is a purpose of my invention to provide a finger board, which is characterized by its ability to support in vertical stacked position within a derrick as many sections of pipe or tubing as is necessary in the drilling or pumping of relatively deep wells and to hold the sections with such security as to prevent them falling from stacked position, and yet permitting single removal of the sections for use in the hole.

I will describe only one form of finger board embodying my invention, and will then point out the novel features thereof in claims.

In the accompanying drawings:

Fig. 1 is a view showing in horizontal plan section a conventional form of derrick having applied thereto one form of finger board embodying my invention with pipe sections in applied position thereon.

Fig. 2 is a vertical sectional view taken on the line 2—2 of Fig. 1.

Fig. 3 is an enlarged sectional view taken on the line 3—3 of Fig. 2.

In carrying out my invention, I provide a supporting member 15 in the form of a channel beam which spans and is secured to the vertical corner posts 16 of a conventional form of derrick, the floor of the derrick being indicated at 17. As shown, the beam 15 is secured in horizontal elevated position above the derrick floor, and with the parallel webs 40 of the beam extended outwardly from the derrick, as best illustrated in Fig. 2. The vertical web of the beam is provided at spaced intervals along its length with horizontally disposed slots 18 in each of which a finger board 19 in the form of a flat bar is slidably received so as to be supported horizontally and in spaced parallel relation to an adjacent finger board 19.

Each finger board is provided at spaced intervals along its length with vertical open-

ings 20 in which pins 21 and 22 are adapted to be received. The pin 21 is employed to limit the sliding movement of the finger board inwardly through the beam 15, the pin abutting the upper parallel web of the beam as illustrated in Fig. 2. Should the pin be removed, displacement inwardly of the finger board from the beam is prevented by a terminal extension 23. The pin 22 is at all times disposed within the innermost opening 20 in order to confine brackets against displacement from the finger board.

Each finger board is adapted to receive and support a plurality of such brackets, each bracket being indicated generally at B, and as shown, comprising a sleeve 24 slidable on the finger board, and an arm 25 fixed to the sleeve so as to extend from one edge of the finger board when the bracket is in applied position thereto. This arm 25 is curved to conform to the contour of the drill pipe, or when it is desired to support sucker rods, the construction of the arm may be changed to accommodate them. As illustrated, the brackets on any one finger board are arranged one in advance of the other between the innermost pin 22 and the beam 15, and so that all of the arms are disposed at one and the same side of the finger board, so as to support at that side of the finger board a plurality of pipe or tubing sections.

In practice, as many brackets as there are tubing or pipe sections to be supported on any one finger bar are applied to the finger bar so that the sections are nested within the arms 25 in the manner illustrated in Figs. 1 and 2. As shown in Fig. 2, the pipe or tubing sections indicated at 26 are slightly inclined when in stacked position against the brackets and consequently they exert a force inwardly along the finger board which tends to slide the board inwardly until the pin 21 abuts the beam 15. Thus with the sections stacked as described, the arms 25 are moved to abutting relation to an adjacent section so that the sections and arms occupy the positions as best illustrated in Fig. 1. Where it is desired to support a minimum number of pipe sections upon any one finger board and so as to hold the pipe sections adjacent the

- beam 15 in an out of the way position, the effective length of the finger board may be shortened by readjustment of the pin 21 in the openings 20 so as to limit the inward sliding movement of the finger board under the weight of the pipe section. For example, if only three brackets B are applied to a finger board for supporting three sections of pipe, the pin 21 will be extended through that opening 20 second from the opening in which it appears in Fig. 1, thus restricting the effective length of the finger board to accommodate the three brackets for holding the three pipe sections.
- 15 To remove pipe sections from the finger boards it is only necessary to remove the inner pins 22 when the pipe sections may be removed together with the brackets.
- Although I have herein shown and described only one form of finger board embodying my invention, it is to be understood that various changes and modifications may be made herein without departing from the spirit of the invention and the spirit and scope of the appended claims.
1. In combination, a derrick, a support thereon, a finger board slidably mounted thereon, means for securing the finger board against movement in one direction, brackets 20 on the finger board extending laterally therefrom for supporting pipes in inclined position, said brackets being slidable on the finger board, and means for securing the brackets against displacement from the finger board.
2. In a derrick, a support, a plurality of finger boards slidable on the support, pipe engaging brackets mounted on the finger boards for sliding movement and to receive pipes therein, means for limiting sliding movement 40 of the finger boards in the support under the action of the pipes when in the brackets, and means for limiting sliding movement of the brackets on the finger boards under the action of the pipes.
3. In a derrick, a support having a slot therein, a finger board slidable in the slot of the support, a pin in the finger board at one side of the support for limiting sliding movement of the finger board in one direction, a plurality of brackets slidable on the finger board at the opposite side from that of the pin, said brackets having means for holding pipes in vertical position, and a second pin in the finger board for confining the brackets 55 on the finger boards.
4. A device of the character described comprising a support, a finger board slidable on the support, means for limiting sliding movement of the finger board in one direction on the support, a plurality of pipe holding brackets slidable on the finger board, and means for confining the brackets against displacement from the finger board.
5. A device of the character described comprising a support, a finger board slidable in

the support and provided at intervals with openings, a pin extendable through any one of the openings for limiting sliding movement of the finger board in the support in one direction, a plurality of pipe holding brackets 70 slidable on the finger board, and a second pin engaging the outermost bracket for confining all of the brackets against displacement from the finger boards.

6. In a derrick, a support thereon provided at intervals with slots, finger boards slid- 75 able in the slots and having adjustable means for limiting sliding movement of the finger boards therein in one direction, pipe supporting brackets on the finger boards, and means for confining the brackets against displacement from the finger boards.

7. In combination, a support adapted for attachment to a derrick, and a finger board on the support having brackets thereon against each of which a pipe in inclined position is adapted to be placed and held, the brackets being mounted on the finger board to move in response to placing of pipes there- 90 against to cause the brackets to occupy a stacked arrangement on the finger board and the pipes a corresponding arrangement.

8. A combination as embodied in claim 7 wherein the means is provided on the finger board for permitting the brackets to be re- 95 moved and replaced to and from the finger board so as to leave on the latter brackets corresponding in number to the pipes to be supported by the finger board.
